W. J. KENNEDY

GAME DEVICE

Filed Aug. 5, 1924

INVENTOR
Walter J. Kennedy
BY
Howard C. Thompson
ATTORNEY

UNITED STATES PATENT OFFICE.

WALTER J. KENNEDY, OF NEW YORK, N. Y.

GAME DEVICE.

Application filed August 5, 1924. Serial No. 730,142.

To all whom it may concern:

Be it known that I, WALTER J. KENNEDY, a citizen of the United States, and residing at New York, in the county of New York and State of New York, have invented certain new and useful Improvements in Game Devices, of which the following is a specification, such as will enable those skilled in the art to which it appertains to make and use the same.

This invention relates to games and particularly to a device of this class of simple construction, which is designed to amuse both young and old; and the object of the invention is to provide a game device comprising a perforated gameboard with means for supporting the board on a floor or other surface whereby a ball or other object may be moved over such surface to enter and pass through the apertures in the gameboard, and to characterize the apertures to give different values thereto; a further object being to provide a game of the class specified which is very inexpensive to manufacture by reason of the simplicity of its construction, and whereby the game may be classed with games sold at retail for ten cents or less than ten cents, and further whereby the game may be compactly folded together and sold in a flat or compact package; and with these and other objects in view, the invention consists in a game device of the class and for the purpose specified constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a perspective front view of my improved game device showing the same mounted in position for use.

Fig. 2 is a side view of the construction shown in Fig. 1; and,

Fig. 3 is a detail view of one of the easels which are employed, detached.

My invention pertains to a game device which is of such simple and inexpensive construction as to permit of its manufacture and sale at a retail price as low as ten cents, or even lower if desired, whereby an interesting and attractive game may be purchased at a very nominal expense or whereby the

game may be given away as a premium by manufacturers, distributors or retail dealers, and in carrying my invention into effect I provide an elongated board 5 which may be composed of heavy paper, cardboard or similar material and longitudinally of the board 5 and adjacent one side edge thereof and opening through said side edge are spaced apertures 6, 7 and 8, three of which are shown in the accompanying drawing and these apertures may be given different values or counts by any suitable designating or characterizing lines, said apertures being characterized, in the construction shown, by the numerals 10, 25 and 5, on the board 5, over the apertures 6, 7 and 8 respectively. It will also be understood that the front face of the board may be printed or otherwise characterized to give attractiveness to the game.

Secured to the back of the board 5 adjacent the end portions thereof are two easel members 9, which are also preferably formed from heavy paper or cardboard and which are fashioned to form a flap portion 10 adapted to be glued or otherwise fixed to the board 5 or the back face thereof and a triangular easel portion 11 foldable on the flap on the line 12. Centrally of the easel 9 is formed a lock member 13 by cutting the easel on the lines 14 by a suitable die or in any other desired manner, and scoring the easel by a score line 15 to permit the folding of the member 13 at right angles to the flap 10 when the triangular easel portion 11 extends at right angles to said flap as shown in Figs. 1 and 2 of the drawing. In this position of the parts, the member 13 rests upon a seat portion 16 formed by the lines 14 in the member 11, and the central recess 17 of the member 13 enters the corner portion 18 in the member 11 formed by the line 14 as will be apparent.

It will be understood that both of the easels 9 are of the same construction, and when the game is not in use, the portions 11 are foldable upon the back face of the board 5 as are also the members 13, and said parts may be extended and locked in position as shown in Figs. 1 and 2, whenever desired.

A ball 19 or other member is employed in connection with and constitutes a part of the game and is adapted to be rolled over a floor or other surface and passed through one of the apertures 6, 7 and 8 in the board 5 to

score predetermined points or counts in whatever manner in which the game may be played.

Heretofore, it has been customary in games of the class under consideration to so construct the same as to materially increase the cost of production thereof, and thus materially increase the retail sale price of the game, and the sole purpose of my improved game device is to so simplify and specifically construct the game as to permit of its manufacture and sale at a retail price of ten cents or less, the entire game being composed of the board 5 with suitable means for supporting the same in an upright or substantially upright position, and the provision of a ball or other member mounted in connection therewith and also the provision of a suitable box or container, not shown, for the two parts of the game. It will also be understood however that the game or the several parts thereof may be made of more expensive material if desired, but it is preferred that the same be made of inexpensive, light and yet strong and durable material, and while I have shown certain details of construction for carrying my invention into effect, it will be understood that I am not necessarily limited in this respect and various changes in and modifications of the construction herein shown and described may be made within the scope of the appended claims without departing from the spirit of my invention or sacrificing its advantages.

Having fully described my invention, 35 what I claim as new and desire to secure by Letters-Patent, is:—

1. A game device of the class described comprising an elongated board member provided longitudinally of one side edge thereof with spaced apertures, means foldable onto one face of said board member for supporting the same when extended at right angles to the board members in an upright position, said means comprising easels and members formed from said easels and cooperating therewith for retaining the same in an extended position.

2. A game device of the class described comprising a member composed of an elongated strip of cardboard fashioned to form a plurality of spaced apertures opening outwardly through one side edge thereof, means for characterizing said apertures, easels secured to the back face of said member adjacent the end portions thereof and adapted when the game is not in use to lie flushly on said member, and when extended backwardly and at right angles to said board member to support said member in a substantially upright position, and means forming part of said easels for retaining the same in an extended position.

In testimony that I claim the foregoing as my invention I have signed my name this 1st day of August, 1924.

WALTER J. KENNEDY.
